ATTORNEY

UNITED STATES PATENT OFFICE.

BEVERLEY RANDOLPH SCOTT, OF WOODLYNNE, NEW JERSEY, ASSIGNOR TO THE HAM-MARLUND MANUFACTURING COMPANY, INCORPORATED, A CORPORATION OF NEW YORK.

COIL CONSTRUCTION.

Application filed February 19, 1926. Serial No. 89,292.

My invention relates particularly to wire coils used for various purposes such as electric inductances.

One object is to provide a coil of high inductance value and low dielectric loss, relatively low resistance and small distributed capacity.

Another object is to provide a coil which can be readily handled and mounted.

10 Another object is to provide a coil having permanent and uniform characteristics.

I have solved the problem by the simple expedient of winding a coil upon a very thin layer of dielectric material to which it is 15 permanently anchored. The method of manufacture which will be hereinafter described makes it possible to maintain any desired spacing of the various turns.

Fig. 1 is a side view of the coil made 20 according to my invention.

Fig. 2 is an end view of the same.

Fig. 3 is a perspective view of a mandrel showing one method of applying the dielectric.

25 Figs. 4 and 5 are diagrammatic end views of two other arrangements of the supporting dielectric.

Fig. 6 is a diagrammatic end view of a coil of angular cross-section supported on 30 two strips of dielectric.

Fig. 7 is an enlarged longitudinal sectional view showing a fragment of a coil in process of manufacture.

Fig. 8 is a similar sectional view showing 35 the same after the wire has been permanently secured in place.

The foundation 10 of the coil is made up of one or more strips of a material such as a 40 nitro-cellulose composition, for instance, celluloid or pyroxylin.

The conductor 11 is covered with insulating material 12 such as silk or cotton fibre.

In making the coil I preferably employ a mandrel 13 made up of a series of sections 45 such as shown in Fig. 3 and provided with a tapered shaft 14 capable of expanding and supporting the mandrel. According to the preferred method of manufacture, a very thin sheet of celluloid, say five-thousandths 50 of an inch thick, is wrapped around the mandrel and the edges of the sheet overlapped, as indicated in Fig. 3, and stuck together by the simple expedient of applying a suitable solvent, such as ethyl-acetate to the material along the line of overlap, 55 the edges of the sheet to be drawn together smoothly and pressed together immediately after the solvent is applied. I have found that this operation of cementing the edges together on the mandrel can be most conveniently affected by the use of a sphincter spring 15. This spring normally rests in a groove 16 in one end of the mandrel and is run along the surface of the celluloid as soon as the overlapping edges have been 60 moistened with the solvent. Springs 16' hold the mandrel parts together. When the edges of the strip have been united on the mandrel, the mandrel is expanded in the usual manner by simply driving the shaft 70 longitudinally. This places the celluloid tube under tension. The mandrel is then placed in a winding machine and the wire wound on it under tension. This tension should remain substantially constant 75 throughout the winding operation and the feeding of the wire should of course be at the proper rate to lay the wire with the desired spacing between adjacent turns. When the coil has been wound, a suitable solvent, such as ethyl-acetate is applied to the 80 foundation between the adjacent turns of the wire, for instance, by means of a brush. This solvent penetrates the insulation of the wire and immediately softens the surface of the foundation. The coil being under tension, as before described, of course tends to 85 contract in diameter and thus sinks very slightly into the softened surface of the celluloid or the like. The change in condition 90 before and after the application of the solvent is shown by the difference between the relative positions of the coil and foundation as shown in Figs. 7 and 8. The mandrel may be contracted and withdrawn as soon as 95 the material has hardened, which requires only a few minutes. The finished coil will, however, continue to dry out for some time, the length of time varying with the composition of the material, the nature of the solvent, and the amount applied, as well as the atmospheric conditions. In drying out the coil shrinks lengthwise, sometimes as much as 10% and becomes corrugated in the longitudinal section as shown in Fig. 8. These 100 corrugations remain permanent and tend to hold the coils in position even if they become loosened from the celluloid.

It is obvious that the coil may be wound at any length desired for special purposes. The method of manufacture lends itself particularly to the production of long tubes 5 which can be readily cut up into such lengths as may be desired.

In the manufacture of these tubes, particularly in small sizes, there is sometimes a tendency for the tube to warp when made 10 as above described, due to the overlapped joint along one edge. This can be readily avoided, however, by using two strips, such as 20 and 21, as shown in Fig. 4, so that there will be oppositely disposed joints 15 which will offset each other in the shrinking process.

It should also be understood that any number of foundation strips may be used and that these strips may be spaced apart as 20 shown for instance in Fig. 5. Here I have shown four strips 23 with spaces 24 between them. A coil wound in this manner has an added advantage of reducing the dielectric material to a minimum.

25 The forms shown in Figs. 5 and 6 are specifically claimed in my application #209,277, filed July 29, 1927.

Although the coil is preferably circular in cross-section, it should be understood that 30 certain features of the invention are applica-

ble to coils of other cross-sections, for instance, in Fig. 6, I have shown a square coil wound on two strips 25 on opposite sides. This would, of course, leave the wires 26 on the other sides spaced apart without supports except at the edges of the strips 25.

Coils wound according to my invention may be used for various purposes, such, for instance, as radio frequency variable couplers, antenna couplers, interstage couplers, 40 neutrodyne coils, short wave coils, etc.

The method of forming coils according to my invention is claimed in my Patent #1,643,998, dated Oct. 4, 1927.

I claim:

1. A self supporting coil comprising a tubular foundation of thin material such as sheet celluloid of substantially uniform thickness, and a helix of wire cemented in the outer surface of the foundation, the foundation being corrugated and the turns of the wire helix being cemented in the grooves of the corrugations.

2. A coil comprising a foundation sheet of thin celluloid-like material having its 55 edges overlapping and cemented together to form a tube and a helix of wire slightly embedded in the outer wall of the foundation tube and cemented therein.

BEVERLEY RANDOLPH SCOTT.
